BEVERAGE DISPENSER

Dewey H. Dolison, Mount Vernon, and Wallace R. Kromer, Cleveland, Ohio, assignors to Oil Heating Devices, Inc., Cleveland, Ohio, a corporation of Ohio

Application February 9, 1937, Serial No. 124,808

19 Claims. (Cl. 225—1)

This invention relates to a method and apparatus for dispensing a beverage, such as beer and the like, and more particularly to a unitary device for serving such beverages directly from the container in which they are transported, and in which the beverage may be cooled before being dispensed.

It is an object of the present invention to provide a dispenser having adjustable means by which the resistance to the flow of beverage being dispensed may be regulated.

More specifically, this invention aims to provide such a flow-resistance regulator that can be manipulated while the beverage is flowing through the dispenser to obtain the most desirable dispensing conditions so that the beverage being dispensed will be fresh and palatable, with a desired amount of foam or collar and carbon dioxide content.

20 Another object is to provide a dispenser of this character which includes means for maintaining the beverage which has been withdrawn from the interior of the original transportation container, but which has not yet been dispensed, within a suitable temperature range.

25 A further object is to provide a beverage dispenser which is simple in design and construction, and inexpensive to manufacture, and one in which the beverage being dispensed has a minimum contact with metallic surfaces.

30 Other objects and advantages will become apparent as the description of the invention proceeds. This description is made in connection with the accompanying drawing, in which like parts in the several views are identified by the same numerals of reference.

Figure 1 is a side elevation, with parts broken away, of a beverage dispensing unit embodying the present invention;

40 Fig. 2 is an enlarged elevational view, partly in section and with parts broken away, showing the dispenser illustrated in Fig. 1;

Figs. 3, 4, 5 and 8 are sectional views taken on the indicated lines of Fig. 2;

45 Fig. 6 is a fragmentary view, in section, showing a modification of the invention; and

Fig. 7 is a sectional view on line 7—7 of Fig. 6.

The present invention is used to advantage in connection with a beverage dispensing system in which the beverage is received from the manufacturer or brewer in a container, such as a barrel or keg 1. It is preferable that the beverage be cooled before being dispensed. In some cases the beverage will already be cool when received from the manufacturer or brewery. However, it

is desirable that some means be provided for cooling the beverage and maintaining it at a desirable temperature. This may be accomplished in various ways, such as by placing the container in a cooling cabinet, or setting it in a tub of cooling liquid, such as ice water or brine.

A more convenient and effective method is illustrated in Fig. 1. The container or barrel 1 is provided with a cooling liquid coil 2, which is preferably carried within the beverage retaining space in order to contact the beverage, and is provided with an inlet 3 and an outlet 4 which communicate with the exterior of the container, so that suitable connections may be made to circulate a cooling liquid through the coil 2.

To open or tap the barrel or container, a fitting 5 is applied to the tap hole of the container and the inlet end 6 of a tubular conduit 7 of the combined tap rod and dispenser illustrated in the drawing is placed in a central aperture in the tap hole fitting 5. This aperture is in alignment with the tap or bung hole of the container, and, upon forcing the tubular conduit 7 into the container, the cork or bung which fills the tap hole is displaced and the tubular conduit 7

may be slid into the container until a footing member 8 on the inlet end 6 of the tubular conduit rests against the bottom of the container, as illustrated in Fig. 1. The tap hole fitting 5 is provided with a pair of rubber jam washers, one of which is arranged to provide a tight seal between the fitting and the tubular conduit 7 by rotation of the upper wing member 9, and the other of which is arranged to provide a tight seal between the fitting and the container 1 by means of the lower wing member 10.

An air or gas conduit 11 is connected to the fitting 5, so that air or a suitable gas such as CO₂ may be supplied to the space in the container 1 over the beverage and maintained at a suitable pressure in the usual manner, it being understood that the central aperture in the fitting 5 communicates with the interior of the container. A valve 12 is provided to regulate the supply of air or gas to the container in the usual manner.

The tubular conduit 7 is of sufficient length to extend a short distance above the keg or container 1, and carries on its outer end a pressure throttling or regulating head 14, which has its inlet end 13 secured to the tubular conduit 7 in any suitable manner, such as by welding or brazing, indicated at 15. The central portion of the pressure regulating head 14 is formed with an elongated tapering bore 16, which extends as a continuation of the central aperture in the tubu-

lar conduit 1. Carried within the tapering bore 16 is a pressure throttling valve body 17, which is in the form of an elongated cone having a taper preferably corresponding to the taper of the bore 16. This valve body is supported and adjustably carried by a stem 18, which has a threaded portion 19 engaged in a capping member 20 of the pressure regulating head.

A knurled thumb wheel 21, carried on the outer squared end of the stem 18, affords the means by which the stem 18 may be screwed into or out of the capping member 20 to advance or retract the valve body 17 with respect to the tapered bore 16, so that the cross-sectional area of the beverage passage through the pressure regulating head 14 may be adjusted to secure the desired amount of frictional resistance to the flow of beverage being dispensed.

A suitable packing material 23, such as cotton yarn, is placed around the stem 18 of the valve body and within a packing chamber formed in the outer portion of the capping member 20 and retained between a pair of packing rings 24 and 25. A packing gland or follower 26 is arranged to have threaded engagement with the capping member 20, so as to retain the packing material 23 in position and adjustably regulate the pressure thereon, thus providing an effective gas and liquid-tight seal between the stem of the valve body and the capping member 20.

The beverage passage in the pressure regulating head is formed at the top of the head into a chamber 28 which communicates with the outlet or terminal end of the tapered bore 16. A laterally extending aperture communicating with the chamber 28 is threaded to receive a tap or faucet 29, which may be of conventional construction.

The passage through the tap or faucet 29 communicates with the chamber 28 in the pressure regulating head so that a continuous passage is provided for the dispensing of beverage from the container 1. A valve body 30 is arranged to be actuated by the knob 31 to open and close the passage through the tap 29 in order that the beverage may be dispensed as desired.

The narrow end of the conical valve body 17 is positioned and maintained in alignment in the passage through the pressure regulating head 14 by a plurality of webs 32 which are formed to extend radially outward from a pin 33 which extends as a continuation of the valve body 17 along the longitudinal axis thereof. The outer edges of the webs 32 are arranged to have sliding engagement with a portion 34 of the passageway through the pressure regulating head 14. The passage portion 34 is of cylindrical cross-section in distinction to the tapered bore 16 in order that the webs 32 may have continuous contact with the walls of the passage to assure proper alignment of the valve body 17 as it is moved longitudinally in the passage by adjustment of the wheel 21.

A modified method of guiding the valve body 17 is illustrated in Figs. 6 and 7. An enlarged passageway 56 is formed in the inlet end 43 of the pressure regulating head 14 and has a circular bearing element 57 positioned therein and held in place by a press fit. A central aperture formed in a transverse rib 59 of the element slidably receives a cylindrical pin 60 which is formed as an extension of the small end of the valve body 17. Beverage flows past the bearing element 57 through a plurality of apertures 58. The enlarged passageway 56 compensates for the

obstruction of the passageway caused by the transverse rib 59 of the bearing element 57 so that there is a minimum of obstruction to the flow of beverage. Desirably the upper end of the wooden lining 45 is trimmed to provide a flared opening from the passageway in the tubular conduit 1 into the enlarged passageway 56 as indicated at 61 to facilitate a streamline flow of the beverage.

In order that the beverage being dispensed will be at a desirable temperature a tubular jacket 35 is formed around the outer end of the tubular conduit 1 which extends from the container 1 and around the pressure regulating head which is carried by the outer end of the tubular conduit. The jacket 35 is in spaced relation with respect to the pressure regulating head and tubular conduit 1 to provide a cooling liquid chamber 36. The upper portion of the pressure regulating head is flared outwardly at 37 so that the upper portion of the tubular jacket 35 may be secured thereto by any suitable means such as brazing or welding. The jacket 35 as shown in Fig. 2 does not entirely surround the portion of the pressure regulating head to which the tap 29 is secured.

The bottom of the tubular jacket 35 is formed into an inwardly extending flange 38 which is secured to the tubular conduit 1 by suitable means such as welding or brazing to provide a fluid-tight joint. An inlet tube or nipple 39 is inserted through the flange portion 38 at the bottom of the tubular jacket 35 and secured in place by welding or brazing. By means of this nipple cooling liquid may be supplied to the cooling liquid chamber 35. In similar manner, an outlet tube or nipple 41 is also secured in place through the flange 38 of the jacket, preferably on the opposite side thereof from the inlet tube 39. It is also desirable that the outlet tube 41 be extended upwardly to a portion of the cooling liquid chamber adjacent the top of the pressure regulating head. In this manner a circulation of cooling liquid entirely through the cooling liquid chamber 36 is assured.

It has been found particularly advantageous in a beverage dispenser of this character to provide a non-metallic lining 45 in the tubular conduit 1, preferably formed of wood. Thus the beverage being dispensed from the system has a minimum contact with metallic surfaces. As shown in Fig. 2, the wooden lining extends from the footing member 8, at the bottom of the conduit, to the inlet end 43 of the pressure regulating head 14. This feature of conducting the beverage through a wood-lined passageway is of particular advantage with a brewed beverage such as beer or ale. Apparently the natural flavor of the beverage is not impaired and a more satisfactory drink may be dispensed. As illustrated in Fig. 8, the wooden lining 45 may be advantageously formed in two or more parts, each of which is arranged to extend the full length of the desired wooden lining and each of which forms a continuous portion of the passage through the conduit.

The footing member 8 previously mentioned comprises a cylindrical body element 50 having a central aperture continuous with the passageway through the tubular conduit 1. The body element 50 threadedly engages the lower end of the tubular conduit 1 and may seat against the wooden lining 45 to assist in retaining the lining in place. Positioned transversely of the aperture through the body element 50 and across the end 76

thereof is a cap 52. This cap preferably has a substantially flat outer surface to seat against the bottom of the container 1 and is held in spaced relation from the body element 50 by 5 projecting portions 53 of the body element. Between the element 50 and cap 52 and between the projections 53 there is thus formed a plurality of elongated openings 54 through which the beverage flows when entering the passage of 10 the unitary dispensing device. It is apparent that the elongated openings 54 are closely adjacent the bottom of the container 1. Accordingly, a dispenser constructed according to the 15 present invention is adapted to withdraw substantially all of the beverage from a container. In addition, the elongated openings are more efficient to pass beverages such as beer and the like, since the carbon dioxide content of the 20 beverage is apt to be disturbed if the flow of the beverage is turbulent. Apparently the elongated openings afford a smoother and more uniform flow of the beverage than other constructions.

The outer flat surface of the cap 52 is of advantage since it is necessary, in tapping a keg, that this portion of the tap rod press against the cork or bung when the latter is dislodged from the bung hole. The wide, flat surface of the tap 25 52 which may extend across nearly the entire 30 diameter of the bung hole is effective in facilitating a uniform and evenly distributed pressure on the bung during a tapping operation.

As previously mentioned, in order to maintain the beverage being dispensed at a desirable temperature, a suitable cooling liquid such as water 25 or brine is supplied to the dispensing unit 30 through the conduit 62. The water flowing through the conduit 62 is divided at a T-fitting 63 into two branches, one branch flows through 35 the conduit 64 to the inlet of the cooling liquid chamber 36. The other branch flows to the inlet 3 of the cooling liquid coil 2 in the container 1 through a conduit 65. In order that the 40 amount of cooling liquid flowing through the cooling liquid chamber 36 may be individually controlled, a regulating valve 66 which 45 may be of any suitable well known design, is placed in the conduit 64 between the T-fitting 63 and inlet 39. Similarly, a regulating valve 67 interposed between the T-fitting 63 and inlet 3 to the container cooling 50 coil 2 permits control of the flow of cooling liquid into the cooling means for the beverage in the original container. By suitable adjustment 55 of the regulating valve 66 with respect to the regulating valve 67 the relative flow of cooling liquid through the cooling liquid chamber 37 with respect to the flow through the cooling liquid coil 2 may be adjusted so that the most 60 desirable conditions of cooling and temperature range are obtained.

The spent cooling liquid flowing out of the cooling liquid chamber 36 through the outlet tube 41 is conducted through the conduit 68 to the outlet T-fitting 69 where it commingles with the spent cooling liquid flowing from the outlet 4 of the cooling liquid coil 2 through the conduit 70. A discharge or return conduit 71 receives the spent cooling liquid from both the cooling liquid chamber 36 and the cooling liquid coil 2 at the T-fitting 69 and either returns it to the refrigerating apparatus which cools it preparatory to its being recirculated through the dispenser or discharges it to waste in accordance 75

with the particular form of refrigerating system employed.

The regulated flow of cooling liquid through the chamber 36 and cooling coil 2 maintains the beverage in the container 1 and that being dispensed through the tap 29 within a desirable temperature range so that the beverage is tasty and palatable. Upon opening tap 29 by movement of the valve body 30 away from its seat, the pressure maintained on the beverage within the container 1 by the air or gas from the conduit 11 forces the beverage through the elongated openings 54 in the footing member 8 and upwardly through the tubular conduit 1. Within this conduit the beverage flows through the passageway in the wooden lining 45 thus being kept out of contact with any metallic surfaces until reaching the pressure regulating head carried by the top of the tubular conduit 1. In passing through the tapering bore 16 and around the tapered valve body 17 of the pressure regulating head, a smooth and streamlined flow of beverage is maintained due to the absence of obstructions or substantial disturbances to its flow. This smooth flow of the beverage facilitates its being dispensed in a desirable condition with a maximum percentage of its original carbon dioxide content still maintained in the absorbed state.

When a fresh keg or container of beverage is tapped with a unitary dispenser constructed in accordance with the present invention and the flow of cooling liquid is adjusted to obtain desirable temperature conditions in the tubular jacket 35 and within the container 1, the operator or bar tender can regulate or control the character of beverage being dispensed by suitable manipulation of the valve body 17 within the pressure regulating head of the dispenser. This may be accomplished by opening the tap 29 so that the beverage flows freely therefrom under the influence of whatever pressure is maintained within the container 1 by means of the air or gas conduit 11. With the beverage thus flowing, the tapered valve body 17 is moved longitudinally in the tapering bore 16 by screwing the threaded stem inwardly or outwardly by means of the knurled hand wheel 21. As the valve body 17 is advanced into the tapering bore 16 the cross-sectional area of the passageway through the pressure regulating head effective for the flow of beverage is diminished. Conversely, as the tapering valve body is withdrawn from the bore 16 the cross-sectional area of the passage available for the flow of beverage is increased. By observation of the beverage flowing from the tap 29, the operator or bar tender can determine when the proper dispensing condition is obtained and the pressure regulating head is then set for the beverage being dispensed from the particular container. Subsequent opening and closing of the valve in the tap 29 to withdraw beverage as required, does not disturb this setting of the pressure regulating head so that successive quantities of beverage may be withdrawn at intermittent intervals which are of a substantially uniform character. Thus a simple and effective adjustment is provided so that the dispensing conditions for each keg or container may be individually regulated. This feature is of particular advantage in dispensing malt beverages such as beer and ale, since, due to various factors and on account of the beverage being purchased from different breweries or manufacturers, each successive

5 container put on tap by a retail establishment is not necessarily identical with that preceding. It sometimes becomes necessary for more or less pressure to be maintained on the beer in the container 1 by regulating the pressure of the gas or air admitted through the conduit 11. Regardless of the pressure maintained on the beer within the container it is possible, however, by the previously mentioned adjustment of the 10 tapered valve body 17 to throttle or reduce the pressure of the beverage flowing through the tapered chamber 16 so that the beverage being dispensed from the tap 29 is of suitable character and retains substantially all of the original 15 carbon dioxide content established by the particular manufacturer or brewer.

10 The dispenser shown in the drawing and described above is for purposes of illustration only, and it is to be understood that numerous modifications in construction and design are contemplated and intended to be included within the scope of the appended claims:

What we claim is:

1. The method of conditioning and dispensing 25 a beverage such as beer and the like which comprises cooling the beverage in the container in which the beverage is transported to substantial dispensing temperature, maintaining a gas pressure on the beverage in the container sufficient 30 to retain substantially all of the original gas content of the beverage in the absorbed state, conducting the beverage over a short path from the container to a receptacle from which the beverage is to be consumed, the path being substantially 35 straight and substantially without turns or bends and of a length insufficient to independently reduce the pressure on the beverage to dispensing pressure, opening and closing the path adjacent the dispensing end thereof to start 40 and stop the dispensing of beverage from the container to maintain substantially uniform pressure on the beverage throughout substantially the whole dispensing system when the path is closed and adjusting the drop in the pressure on the 45 flowing beverage being drawn at a portion of said path intermediate the dispensing end thereof and the end within the container, independently of said opening and closing, whereby substantially the entire drop in pressure on the flowing beverage may be initially determined for each 50 container and maintained constant and independent of the opening or closing of the path.

2. The method of conditioning and dispensing 55 a beverage such as beer and the like which comprises cooling the beverage in the container in which the beverage is transported to substantial dispensing temperature, maintaining a gas pressure on the beverage in the container sufficient 60 to retain substantially all of the original gas content of the beverage in the absorbed state, conducting the beverage over a short path from the container to a receptacle from which the beverage is to be consumed, the path being substantially straight and substantially without turns 65 or bends and of a length insufficient to independently reduce the pressure on the beverage to dispensing pressure, opening and closing the path adjacent the dispensing end thereof to start and stop the dispensing of beverage from the container 70 to maintain substantially uniform pressure on the beverage throughout substantially the whole dispensing system when the path is closed, adjusting the drop in the pressure on the flowing beverage being drawn at a portion of said 75 path intermediate the dispensing end thereof and

the end within the container, independently of said opening and closing, whereby substantially the entire drop in pressure on the flowing beverage may be initially determined for each container and maintained constant and independent of the opening or closing of the path, and cooling the beverage over a portion of said path and while the pressure on the beverage is being reduced.

3. A dispenser for drawing a beverage such as 10 beer and the like directly from a container in which the beverage is transported, comprising a tubular conduit substantially straight and substantially without turns or bends, said conduit having an intake end receivable in the container and arranged to be immersed in the beverage, and a dispensing end extending only a short distance from the container, a tap at the dispensing end of the conduit having valve means arranged to operably permit the withdrawal of beverage from the container through the conduit, and means carried by the conduit and independent of said valve means for adjustably regulating the resistance to the flow of beverage through the conduit, said last named means being adjustable while beverage is being drawn from the container, whereby the most desirable resistance to flow for each container may be individually selected and is maintained regardless of the number of times beverage is drawn.

4. A dispenser for drawing a beverage such as 20 beer and the like directly from a container in which the beverage is transported and in which the beverage is maintained under pressure, comprising a tubular conduit having an intake end 25 receivable in the container and arranged to be immersed in the beverage and a dispensing end extending only a short distance from the container, a tap at the dispensing end of the conduit having valve means to operably permit the withdrawal of beverage from the container through the conduit under the influence of said pressure, and a wooden lining in the conduit arranged to decrease the effective cross-sectional area of the beverage passage through the conduit, said lining being supported by the conduit and extending substantially from the inlet end to adjacent the dispensing end, whereby beverage being drawn from the container has a minimum contact with metal.

5. A dispenser for drawing a beverage such as 30 beer and the like directly from a container in which the beverage is transported and in which the beverage is maintained under pressure, comprising a tubular conduit having an intake end 35 receivable in the container and arranged to be immersed in the beverage and a dispensing end extending only a short distance from the container, a tap at the dispensing end of the conduit having valve means arranged to operably permit the withdrawal of beverage from the container through the conduit under the influence of said pressure, means carried by the conduit for adjustably regulating the resistance to the flow of beverage through the conduit, said last named means being independent of the valve means and being adjustable while the beverage is being drawn from the container whereby the most desirable resistance to flow for each container may be individually selected and is maintained regardless of the number of times beverage is drawn, and a wooden lining in the conduit arranged to decrease the effective cross-sectional area of the beverage passage through the conduit, said lining being supported by the conduit and

extending substantially from the inlet end substantially to the flow resisting means whereby beverage being drawn from the container has a minimum contact with metal.

5. 6. A dispenser for drawing a beverage such as beer and the like directly from a container in which the beverage is transported, comprising a substantially straight tubular conduit having an intake end receivable in the container and arranged to be immersed in the beverage, and a dispensing end extending only a short distance from the container, a cooling liquid chamber formed to surround a portion of the conduit extending from the container, means whereby cooling liquid may be circulated through the chamber to maintain said extending portion of the conduit within a desired temperature range, a tap at the dispensing end of the conduit having valve means arranged to operably permit the withdrawal of beverage from the container through the conduit, and means carried by the conduit and independent of said valve means for adjustably regulating the resistance to the flow of beverage through the conduit, said last named means being adjustable while beverage is being drawn from the container, whereby the most desirable resistance to flow for each container may be individually selected and is maintained regardless of the number of times beverage is drawn.

7. A dispenser for drawing a beverage such as beer and the like directly from a container in which the beverage is transported and in which the beverage is maintained under pressure, comprising a tubular conduit having an intake end receivable in the container and arranged to be immersed in the beverage and a dispensing end extending only a short distance from the container, a cooling liquid chamber formed to surround a portion of the conduit extending from the container, means whereby cooling liquid may be circulated through the chamber to maintain said extending portion of the conduit within a desired temperature range, a tap at the dispensing end of the conduit having valve means to operably permit the withdrawal of beverage from the container through the conduit under the influence of said pressure, and a wooden lining in the conduit arranged to decrease the effective cross-sectional area of the beverage passage through the conduit, said lining being supported by the conduit and extending substantially from the inlet end thereof to a region of the conduit surrounded by said cooling chamber and adjacent the dispensing end of the conduit, whereby beverage being drawn from the container has a minimum contact with metal.

8. A dispenser for drawing a beverage such as beer and the like directly from a container in which the beverage is transported and in which the beverage is maintained under pressure, comprising a tubular conduit having an intake end receivable in the container and arranged to be immersed in the beverage and a dispensing end extending only a short distance from the container, a cooling liquid chamber formed to surround a portion of the conduit extending from the container, means whereby cooling liquid may be circulated through the chamber to maintain said extending portion of the conduit within a desired temperature range, a tap at the dispensing end of the conduit having valve means arranged to operably permit the withdrawal of beverage from the container through the conduit under the influence of said pressure, means car-

ried by the conduit for adjustably regulating the resistance to the flow of beverage through the conduit, said last named means being independent of the valve means and being adjustable while the beverage is being drawn from the container whereby the most desirable resistance to flow for each container may be individually selected and is maintained regardless of the number of times beverage is drawn, and a wooden lining in the conduit arranged to decrease the effective cross-sectional area of the beverage passage through the conduit, said line being supported by the conduit and extending substantially from the intake end thereof to a region of the conduit surrounded by the cooling chamber and adjacent the adjustable flow resisting means whereby beverage being drawn from the container has a minimum contact with metal.

9. A tap rod for dispensing a beverage such as beer and the like directly from a transportation container in which the beverage is maintained under pressure, which comprises in a single unitary structure a tubular conduit receivable in a tap hole of a container and of sufficient length when positioned in the tap hole to extend from the lowermost portion of the interior of the container to a position exterior of the container and only a short distance above the top of the container, said conduit being substantially straight and substantially without turns or bends, a pressure throttling head secured to the exterior portion of the conduit and supported thereby, said head having adjustable means for regulating the resistance to the flow of beverage through the rod and a faucet carried by the head, said faucet having means, independent of the adjustable regulating means, for controlling the withdrawal of a beverage from the container through the tap rod.

10. A tap rod for dispensing a beverage such as beer and the like directly from a transportation container in which the beverage is maintained under pressure, which comprises in a single unitary structure a tubular conduit receivable in a tap hole of a container and of sufficient length when positioned in the tap hole to extend from the lowermost portion of the interior of the container to a position exterior of the container and only a short distance above the top of the container, said conduit being substantially straight and substantially without turns or bends, a pressure throttling head secured to the exterior portion of the conduit and supported thereby, said head having adjustable means for regulating the resistance to the flow of beverage through the rod, a faucet carried by the head, said faucet having means, independent of the adjustable regulating means, for controlling the withdrawal of beverage from the container through the tap rod, and a cooling liquid chamber formed to surround an exterior portion of the tap rod and said adjustable pressure throttling head, said cooling liquid chamber arranged to have cooling liquid circulated therethrough to maintain the exterior portion of the tap rod within a desired temperature range.

11. A tap rod for dispensing a beverage such as beer and the like directly from a transportation container in which the beverage is maintained under pressure, which comprises in a single unitary structure a tubular conduit receivable in a tap hole of a container and of sufficient length when positioned in the tap hole to extend from the lowermost portion of the interior of the container to a position exterior of the container, a

wooden lining in the conduit extending substantially from the inlet end thereof positioned within the container to substantially the end thereof positioned exterior of the container, a pressure throttling head secured to the exterior portion of the conduit and supported thereby, said head having adjustable means for regulating the resistance to the flow of beverage through the rod and a faucet carried by the head, said faucet having means, independent of the adjustable regulating means, for controlling the withdrawal of a beverage from the container through the tap rod.

12. A tap rod for dispensing a beverage such as beer and the like directly from a transportation container in which the beverage is maintained under pressure, which comprises in a single unitary structure a tubular conduit receivable in a tap hole of a container and of sufficient length when positioned in the tap hole to extend from the lowermost portion of the interior of the container to a position exterior of the container, a wooden lining in the conduit extending substantially from the inlet end thereof positioned within the container to substantially the end thereof positioned exterior of the container, a pressure throttling head secured to the exterior portion of the conduit and supported thereby, said head having adjustable means for regulating the resistance to the flow of beverage through the rod, a faucet carried by the head, said faucet having means, independent of the adjustable regulating means, for controlling the withdrawal of beverage from the container through the tap rod and a cooling liquid chamber formed to surround an exterior portion of the tap rod, said cooling liquid chamber arranged to have cooling liquid circulated therethrough to maintain the exterior portion of the tap rod within a desired temperature range.

13. A tap rod for dispensing a beverage such as beer and the like from a container in which the beverage is maintained under pressure, comprising a tubular metal conduit having an inlet end adapted to be inserted into a beverage container through a bunghole thereof and having a beverage passage extending longitudinally therethrough, a tubular lining supported in said conduit and materially reducing the cross-sectional area of the beverage passage, said lining being formed of wood and arranged to substantially prevent beverage flowing through the lined passage from contacting the metal conduit, and a footing member secured to the inlet end of the conduit.

14. A tap rod for dispensing a beverage such as beer and the like from a container in which the beverage is maintained under pressure, comprising a tubular metal conduit having an inlet end adapted to be inserted into a beverage container through a bunghole thereof and having a beverage passage extending longitudinally therethrough, a tubular wooden lining circumferentially embraced and supported in said conduit and materially reducing the cross-sectional area of the beverage passage, said lining being formed in sections confined and held in their correct relative positions by the conduit, and a footing member secured to the inlet end of the conduit.

15. A unit for dispensing a beverage such as beer and the like which comprises in combination a container in which the beverage is transported and maintained under pressure, a cooling element in said container having an inlet and an outlet accessible from the exterior of the container and

through which a cooling liquid may be circulated to maintain the beverage in the container within a desired temperature range, a tubular conduit having an intake end in the container, said end being below the surface of the beverage, a pressure regulating head carried by the conduit and having an adjustable means for regulating the resistance to the flow of beverage being dispensed, a tap carried by the head for drawing beverage as required, the operation of said tap being independent of the adjustable regulating means, a cooling liquid chamber formed to surround an exterior portion of the conduit extending from the container, said chamber having an inlet and an outlet whereby cooling liquid may be circulated therethrough to maintain said extending portion of the conduit within a desired temperature range, said outlets arranged so that cooling liquid flowing from the cooling liquid chamber and cooling liquid flowing from the cooling element is commingled and flows away from the unit, and said inlets arranged so that, of the cooling liquid flowing to the unitary device, a portion flows through the cooling liquid chamber and a portion flows through the cooling element.

16. A unit for dispensing a beverage such as beer and the like which comprises in combination a container in which the beverage is transported and maintained under pressure, a cooling element in said container having an inlet and an outlet accessible from the exterior of the container and through which a cooling liquid may be circulated to maintain the beverage in the container within a desired temperature range, a tubular conduit having an intake end in the container, said end being below the surface of the beverage, a pressure regulating head carried by the conduit and having an adjustable means for regulating the resistance to the flow of beverage being dispensed, a tap carried by the head for drawing beverage as required, the operation of said tap being independent of the adjustable regulating means, a cooling liquid chamber formed to surround an exterior portion of the conduit extending from the container, said chamber having an inlet and an outlet whereby cooling liquid may be circulated therethrough to maintain said extending portion of the conduit within a desired temperature range, said outlets arranged so that cooling liquid flowing from the cooling liquid chamber and cooling liquid flowing from the cooling element is commingled and flows away from the unit, said inlets arranged so that, of the cooling liquid flowing to the unit, a portion flows through the cooling liquid chamber and a portion flows through the cooling element, and means for controlling the proportion of cooling liquid flowing through the cooling liquid chamber with respect to the portion which flows through the cooling element, whereby the relative temperatures of the beverage in the conduit extending from the container and the beverage within the container may be regulated.

17. A unit for dispensing a beverage such as beer and the like which comprises in combination a container in which the beverage is transported and maintained under pressure, a tubular conduit disposed in a substantially vertical position and having an intake end in the container, said end being below the surface of the beverage and the conduit being substantially straight throughout its length, a pressure throttling head carried and supported by the conduit and having an adjustable means for regulating the resistance to the flow of beverage being dispensed, a tap car-

- ried and supported by the head for drawing beverage as required, the operation of said tap being independent of the adjustable regulating means, and a wooden lining in the conduit, said lining formed in sections and supported by the conduit, the lining extending substantially from the intake end of the conduit to the adjustable throttling means whereby beverage being drawn from the unit has a minimum contact with metal.
- 10 18. The method of conditioning and dispensing a beverage such as beer and the like which comprises cooling the beverage in the container in which the beverage is transported to substantially dispensing temperature, maintaining a gas pressure on the beverage in the container sufficient to retain substantially all of the original gas content of the beverage in the absorbed state, drawing cool beverage at relatively high velocity through a short substantially straight course of 15 relatively small cross-sectional area extending from substantially the bottom of the container only a short distance above the container to progressively reduce the pressure on the beverage being drawn, said reduction being insufficient to 20 independently reduce the pressure on the beverage to dispensing pressure, adjustably throttling the pressure on the beverage being drawn at the top of the course to complete the reduction of the 25 pressure on the beverage to the desired dispensing pressure, and releasing the cooled beverage at the desired pressure substantially at the top of said 30 course substantially without circuitous flow thereof.
19. The method of conditioning and dispensing a beverage such as beer and the like which comprises cooling the beverage in the container in 5 which the beverage is transported to substantially dispensing temperature, maintaining a gas pressure on the beverage in the container sufficient to retain substantially all of the original gas content of the beverage in the absorbed state, drawing cool beverage at relatively high velocity 10 through a short substantially straight course of relatively small cross-sectional area extending from substantially the bottom of the container only a short distance above the container to progressively reduce the pressure on the beverage being drawn, said reduction being insufficient to independently reduce the pressure on the beverage to dispensing pressure, adjustably throttling the pressure on the beverage being drawn at the top 15 of the course to complete the reduction of the pressure on the beverage to the desired dispensing pressure, enclosing substantially all of the course above the container by a local cooling medium while the pressure on the beverage is being reduced and substantially until the beverage is dispensing, and releasing the cooled beverage at the top of the course substantially at the top of said course substantially without circuitous 20 flow thereof.
